UNITED STATES PATENT OFFICE.

CHARLES MUNDT, OF HOBOKEN, NEW JERSEY.

DESIGN FOR A SANITARY TELEPHONE-MOUTHPIECE.

45,347.

Specification for Design.

Patented Mar. 3, 1914.

Application filed January 5, 1914. Serial No. 810,514. Term of patent 7 years.

To all whom it may concern:

Be it known that I, CHARLES MUNDT, a citizen of the United States, residing at Hoboken, in the county of Hudson and State of New Jersey, have invented a new, original, and ornamental Design for Sanitary Telephone-Mouthpieces, of which the following is a specification, reference being had to the accompanying drawing, forming part thereof.

Figure 1 is a front view of a telephone mouthpiece showing my design; Fig. 2 is a

rear view of the mouthpiece shown in Fig. 1; Fig. 3 is a vertical section through the mouthpiece shown in Fig. 1, part of a telephone being shown in dotted lines.

I claim:

The ornamental design for a sanitary telephone mouthpiece, as shown.

CHARLES MUNDT.
